UNITED STATES PATENT OFFICE.

FRANCIS T. JOHNSON, OF CHICAGO, ILLINOIS.

WASHING-MACHINE.

1,213,202.

Specification of Letters Patent.

Patented Jan. 23, 1917.

Application filed June 7, 1915. Serial No. 32,525.

To all whom it may concern:-

Be it known that I, FRANCIS T. JOHNSON, a citizen of the United States, residing at Chicago, in the county of Cook and State of Illinois, have invented a certain new and useful Improvement in Washing-Machines, of which the following is a specification.

My invention relates to improvements in washing machines and has for one object to provide a new and improved washing machine which shall be safely and easily operated, easily repaired and durable.

It is illustrated more or less diagrammatically in the accompanying drawings, 15 wherein is shown an end elevation in part section with parts omitted of the tub.

Like parts are indicated by like letters throughout.

A⁴ is a tub having a corrugated peripheral wall A⁵ reinforced by a cylindrical band A⁶ and reinforced ends A⁷. Projecting from these reinforced ends A⁷ are axial stubs A⁸ journaled in bearings A⁹ which project inwardly from the frames A, A¹. Along the upper side of the tub is a hopper like opening B having inwardly inclined walls B¹. This opening is closed by a removable cover B² having inwardly extending flanges B³ and inwardly and outwardly extending flanges B⁴ adapted to rest on the walls B¹. This cover is apertured as at B⁵ to permit passage of air and the sole function of this cover is to permit splashing. It lies in position at the bottom of the hopper opening without being locked in any way it being held by its own weight at all times during the operation of the machine.

B⁶ is a baffle bar or cylinder within the tub supported at either end by the side wall 40 and raised slightly above the bottom of the tub so as to permit passage of the water between it and the corrugated tub. In this is located a discharge pipe B⁸ apertured as at B⁹ along its length.

It will be evident that while I have shown in my drawings an operative device, still many changes might be made both in size, shape and arrangement of parts without departing from the spirit of my invention, and 50 I wish, therefore, that my drawings be regarded as in a sense diagrammatic.

It is understood that this wringer tub is adapted to rotate or oscillate, and I have not illustrated or described means for rotating and oscillating it, but it is understood that as the drum rotates back and forth the

liquid contained therein together with the objects in the liquid will be thrown first in one direction and then in the opposite direction moving peripherally about the corrugated tub. The contents in the tub will impinge upon the baffle member. The water or at least some of it will go through the perforate base between the baffle member and the wall of the tub. The remainder will be changed in direction and compelled to go over this baffle member thus agitating the clothes and the liquid and insuring thorough washing. At each end of the travel of the tub the contents are brought up against the inwardly inclined walls surrounding the door and this tends to shunt the material back into the tub and arrest the movement of the water and objects suspended therein. Experience shows that this rotary oscillatory movement in cooperation with the baffle member and inwardly inclined walls results in such sudden changes of direction and motion as to insure that all the foreign matter in the goods being washed or treated is beaten, whipped or driven or otherwise removed from the goods and carried off by the water.

X² is a box interposed between the baffle member and the wall of the tub, and perforated as indicated so that while the liquid may pass through between the baffle member and the wall of the tub, still solids can not do so.

I claim:

1. A washing machine having a substantially cylindrical tub, a cylindrical baffle member contained therein, located between the center thereof and the periphery thereof, and means interposed between the wall of the tub and the baffle member, and located entirely beneath the baffle member and between it and the tub for preventing the passage of solid materials while permitting the passage of liquids through the aperture between the baffle member and the wall of the tub.

2. A cylindrical tub having a cylindrical baffle member therein parallel with its axis, a narrow box located between the baffle member and the wall of the tub and closing the space between them, said box being perforate, the width of the box being less than the diameter of the baffle member.

3. A washing machine having a cylindrical tub, a baffle member therein arranged so as to form two hopper shaped chambers

within the tub on both sides of the baffle member, such hopper-shaped chamber terminating each at a point beneath the baffle member, means interposed at such termination for preventing the passage of solid materials through the space between the tub and the baffle member while permitting the passage of liquids.

In testimony whereof, I affix my signature in the presence of two witnesses this 1st day of June, 1915.

FRANCIS T. JOHNSON.
